TENSION CONTROL FOR PAPER ROLLS
AND THE LIKEJoseph E. McMullen and Charles Stenger,
Milwaukee, Wis.

Application July 9, 1943, Serial No. 493,972

7 Claims. (Cl. 242—58)

This invention relates to improvements in tension controls for paper rolls and the like. The invention has particular utility in the feed of a printing press and is exemplified in drawings showing the application of the invention to a Hoe press.

It is the object of the invention to avoid the over or under tensioning of a new roll at the time of making a "paster" connection. As one supply roll is exhausted, it is moved out of the position in which it is normally subject to automatic tension control and a full roll is moved into such position. At the time the web from the nearly exhausted roll is pasted to the web on the full roll, the peripheral speed of the full roll should not only approximate the perimetral rate of travel from the web of the exhausted roll, but the tension to which the full roll is subjected should approximately correspond with the tension on the web leading from the exhausted roll. If the tension on the full roll is excessive, when the pasted joint is made, the excess may cause the web to break. Insufficient tension will cause a loss of control of the web with consequent spillage of some of the printing and possible breakage of the web.

The matter of arriving at the proper tensioning of a new supply roll at the time of making a "paster" has heretofore been dependent upon the great skill and experience of the operator. It is the primary purpose of the invention to so simplify and render automatic the determination of requisite tension as to greatly reduce the amount of skill and experience required and to assure more perfect results.

Other objects will appear in more detail to those skilled in the art upon analysis of the following disclosure of the invention.

In the drawings:

Fig. 1 is a fragmentary view in side elevation of portions of the tension control mechanism of a printing press as such mechanism appears at the moment when a paster is about to be made.

Fig. 2 is a sectional view of some of the same mechanism, parts being broken away, showing the mechanism in the condition which precedes the making of a paster.

Fig. 3 is a fragmentary detail in plan of portions of the tension control belts and the mounting shaft upon which the belt assemblies oscillate for the control of tension.

Fig. 4 is a detail view in elevation of the end of the belt control shaft opposite to the end shown in Fig. 1.

Fig. 5 is a simplified wiring diagram showing

(relays omitted) the simplified circuits controlled in accordance with the present invention.

Like parts are identified by the same reference characters throughout the several views.

5 The construction and operation of the conventional structure will first be briefly described.

There is a reel at 6 mounted for indexing rotative adjustment and provided with a number of arms supporting the arbors 7 upon which the supply rolls 8, 9 and 10 are mounted. Each of the arbors (or chucks engaged with such arbors) is supplied with its own manually adjustable tension regulating brake at 11.

The web 12 withdrawn from the supply roll 10 15 passes guide rolls 13 and 14 to the rolls 15 and 16 between which the web forms a bight 17 in which the tension controlling roll 18 floats. Thereupon the web passes to the press.

The tension controlling roll 18 is carried by an 20 arm 19 on the rock shaft 20 whereof another arm is subject to the bias of a tension spring 21 urging the roll 18 downwardly. As the tension on the web increases, the roll 18 will yield upwardly against the tension spring 21. As the tension on 25 the web decreases, the roll 18 will move downwardly subject to the bias of spring 21.

The arm 22 connected with rock shaft 20 actuates through link 23 a pair of switches 24, 25 (Fig. 5) in the tension control box 26 (Fig. 1).

30 When the roll 18 moves downwardly due to a decrease in web tension, switch 25 is closed to operate in a downward direction the tensioning device hereinafter to be described. When the tension is excessive, switch 24 is closed by the 35 upward movement of roll 18 to elevate the tensioning device hereinafter to be described.

The tensioning device comprises a pair of belts 30 and 31 extending over pulleys on shaft 32 whereby such belts are driven. The belts also 40 extend about pulleys 33 and 34, respectively mounted on arms 35 and 36 which are oscillatable upon the belt arm shaft 37. Each pulley 33, 34, has its own takeup device which is illustrated in Fig. 2 and Fig. 3 but, comprising no part of 45 the present invention, is not described in detail.

In normal operation, the belts 30 and 31 are 50 maintained in pressure contact with the periphery of the supply roll which is in the operative position of the roll shown at 9 in Fig. 1. The belts operate at a speed slightly slower than the peripheral speed of roll 9 required to feed the web from such roll at the desired rate. The more lightly the belts bear on the roll, the greater will be the slippage and the more pressure that is ex-

erted by the belts upon the roll, the less will be the slippage. Thus tension is controlled by the oscillatory position of shaft 37 which regulates the pressure with which the belts engage roll 8. A reversible motor 38 (Figs. 1, 3, 5) has gear and segment connection to the belt and shaft 37 for adjusting the position of such shaft. The switches 24, 25 in the tension control box 26 normally automatically regulate the forward and reverse operation of motor 38 to produce oscillations of shaft 37 in the requisite direction to adjust the belts 30 and 31 upwardly and downwardly with respect to the supply roll with which they are engaged, thereby automatically regulating the tension to which such roll is subject.

If the automatic downward movement of the belts becomes so excessive as to endanger the apparatus, the motor circuit which operates the belt arms downwardly is broken by emergency limit switches mounted on the respective belt arms and shown at 39 and 40 in Figs. 3 and 5. These switches are in series so that if the lower flight of either belt touches the actuator of either switch the circuit otherwise controlled by the tension increasing switch 25 will be opened. A similar emergency switch is disposed at 42 where its actuator 43 may be engaged by a cam 44 on the belt arm shaft 37 (Fig. 4) to open the circuit otherwise controlled by the tension releasing switch 24, in the event that the upward or tension decreasing movement of the belt arms becomes excessive. For manual control of tension, push button switches are provided at 45 and 46 which (showing of interlocking relays omitted) can be used at any time to take over from the automatic switches 24 and 25 the control of motor 38 and the consequent position of the belt arm shaft 37 and the belts.

In operation, supply roll 10 being almost exhausted, as shown in Fig. 2, the operator manually adjusts tension brake 11 to maintain substantially the same tension on the web 12 as has theretofore been automatically maintained through the adjustment of the tensioning belts 30, 31. As the hand brake 11 becomes operative on the arbor of roll 10, the tensioning belts are lifted to the position shown in Fig. 2 until they are not only free of roll 10 but leave room for the substitution of a full roll.

The reel 6 is now indexed to move the nearly exhausted roll 10 to the position shown in Fig. 1, bringing full roll 9 into position beneath the belts 30, 31. To assist the operator in maintaining by hand brakes 11 the same tension on web 12 which has heretofore been maintained automatically, we provide at 47 a pointer on the rock shaft 20 of the tension responsive arm 19. Plate 48 carries an adjustable indicator 49 with which the pointer 47 will substantially register when the tension is correct.

With the new roll 9 in position, the belts 30 and 31 are lowered into engagement therewith and the roll is set in motion. As above noted, it is critically essential that the tension which will become effective on the new roll at the time the "paster" is made must correspond substantially with the tension on the nearly exhausted roll.

The paster is made through structure and technique well known to the art and will only briefly be described. The operator pulls hand lever 50 and paster lever 51 from their retracted positions of Fig. 2 toward the positions in which such levers are shown in Fig. 1. The brush 53 forces the web 12 into immediate proximity to the periphery of roll 9. As contact of web 12 with the

periphery of roll 9 is achieved, the adhesively treated end of the web on roll 9 adheres to the web 12 and becomes a part thereof and the cut-off knife 54 is concurrently actuated to sever that portion of web 12 coming from the exhausted roll 10. The means by which the cutoff knife is actuated is not shown, being no part of the present invention.

As a step toward the achievement of the results sought by the present invention, we provide a pointer 55 on the operator's end of the belt arm shaft 37 and provide a fixed scale at 56 on the arm supporting such shaft to afford, in conjunction with pointer 55, a reading indicative of the position of the belt arm shaft 37, such position being, in general, correlated to the belt tension exerted on a full roll (as a roll becomes used, the belt arms would have to be lowered to maintain the same tension).

At the other end of shaft 37, as shown in Figs. 3 and 4, we mount on the shaft an oscillatably adjustable arm 57 carrying a cam lobe 58 arranged to interact with cam follower roller 59 on the switch actuator 60 of switch 61 connected in series with push button 45 between the supply line and the down circuit terminal 62 of motor 38. On the cam supporting arm 57, a pointer 64 moves across a scale 65 on the disk portion of cam 44 on the belt arm shaft 37. The reading of pointer 64 on the scale 65 may be set to correspond with the reading which pointer 55 (Fig. 1) should have with respect to scale 56 when the belts engage, at proper tension, a full roll of predetermined diameter.

It will be apparent that the desired position of the belt arms and belts to achieve the predetermined tension on the full roll will be somewhere intermediate the extreme positions of such arms and belts as determined by the emergency limit switches. It will also be intermediate the normal range of operation of the tension belts in response to automatic control of the switches in the tension control box 26 during normal functioning. When this intermediate position is determined to achieve requisite tension, all the operator needs to do, to set such tension, is to push the manually operable switch button 45 until the belt arms are lowered from the elevated retracted position and come to rest. They will come to rest whenever the adjustable cam lobe 58 encounters the cam follower 59 to open switch 61. Thus, the required tension is achieved automatically without requiring any particular skill on the part of the operator.

However, it would not do to have the circuit to motor 38 interrupted during normal operation by any such engagement of the cam lobe 58 with the cam follower 59. Accordingly, we devised means for making the interruption of the down circuit of motor 38 in this manner occur only in the course of making a "paster." To this end, we provide at 70 (Fig. 1 and Fig. 5) a switch shunting switch 61 and biased toward open position. This switch is normally held closed by engagement of cam follower roller 71 with cam lobe 72 on the hand lever 50 which operates the paster arm 51. When the paster lever 50 is moved to the position shown in Fig. 1, the disengagement of its lobe 72 from the roller 71 opens switch 70, leaving switch 61 in control of the circuit. During the raised position of lever 50 in normal operation, the switch 70 is closed, shorting switch 61 out of operation.

In preparing to make a paster, lever 50 is caused by the adjustment of the brush arms to

assume the position shown in Fig. 1 before the belts are lowered on to the new roll. Thus, when the belts are lowered on to the new roll, the switch 70 is open and the switch 61 is therefore left in control of the motor circuit 36 in series with push button switch 45.

There is a brief interval of time after the belts have been moved into proper tension engagement with the new roll during which the predetermined tension might be varied by the automatic switches 24 and 25 in the tension control box 26, but for a further circuit arrangement. It is undesirable during this period to leave the automatic tension controls in effect inasmuch as the floating roll 18 is still governed by the tension of the hand brake 11 on the arbor of the exhausted roll 10, whereas the belts are operating on the new roll 9 during this interval. Since the web is not yet moving from the new roll 9, no change in the tension of the web moving from the exhausted roll should be allowed to shift the belts 38 from their predetermined position. Accordingly, I provide on the bracket 74 to which the paster arm 51 is pivoted a switch or switches 75 (Fig. 2) which are biased toward a normally closed position but are provided with an actuating lever 76 engaged in the oscillation of the paster arm 51 to open the switch or switches through which the automatic control switches 24, 25 are energized. It should be explained that so far as the simplified circuit illustrated in Fig. 5 is concerned, a single switch 75 would appear to serve. In practice, because of the relays actually used, it is preferred that two separate switches 75 be employed (or a double pole switch).

These several changes will be understood by those skilled in the art to greatly simplify the operation of substituting a full roll for the nearly exhausted roll in a press or the like. The automatic controls remain effective throughout the normal unwinding of the web to control the tension. Yet, when a change is being made, these normally operating automatic controls are rendered ineffective and a new set of automatic controls becomes effective without any attention on the part of the operator, but purely incidentally to the routine movements requisite to a change of rolls. There is nothing new for the operator to learn; rather, the skill required of him is less, since the difficult task of predetermining the tension on the new roll, immediately preceding the "paster," is automatically governed in accordance with the setting of one of the special switches provided in accordance with this invention.

We claim:

1. In a web unwinding device of the type having web tensioning means manually controllable as to adjustment preliminary to a "paster," the combination with the tension adjusting member and manually controlled means for the adjustment thereof, of an adjustable limiting device for predetermining the setting to which such member is adjusted, said limiting device comprising means for interrupting the movement of said member irrespective of continued manual control.

2. In a web unwinding device of the type having a belt flight adjustable as to its pressure engagement with an unwinding roll to regulate the tension of a web unwound therefrom and having an arm provided with a guide supporting said belt flight and mounted for adjustment, and a

motor having driving connections for the adjustment of said arm, the combination with said arm of a motor control circuit including a plurality of switches in series, one of said switches comprising a manually operable switch and another comprising a switch mechanically actuated in accordance with the position of said arm to determine a predetermined adjustment thereof, said arm and said last mentioned switch being provided with parts engageable for switch actuation in a predetermined position of said arm to open said last mentioned switch whereby to interrupt the circuit to said motor irrespective of the continued closed circuit position of the manually operable switch, together with a third switch shunting the mechanically operated switch and normally closed to render said mechanically operable switch ineffective to open the circuit, a handle operable prerequisite to a "paster" operation, and means connected with the handle for opening said third switch upon the movement of the handle, thereby leaving the mechanically operated switch in control of the motor circuit preliminary to a paster operation.

3. A device of the character described comprising in combination a paster arm, a handle connected therewith for the operation thereof, a switch provided with means operable to open the switch upon displacement of the handle and paster arm, a tension belt having a flight movable to and from tension engagement with a supply roll, a belt arm provided with a guide pulley for said belt movable to vary tension on said roll, a rock shaft supporting said arm for adjustment, a second switch normally closed and provided with connections from said rock shaft for opening said switch upon movement of said rock shaft to a predetermined point in a direction of increase of tensioning pressure of said belt upon a roll, a motor provided with driving connections for the oscillation of said rock shaft, a third switch manually operable for the operation of said motor, and a motor circuit in which the first and second switches are connected in parallel with each other and in series with the third switch whereby at least one of the first and second switches must be closed to permit motor operation by means of the third switch.

4. The combination with a roll web tensioning device and a motor for the adjustment thereof having normally operative automatic switch controls, of auxiliary circuit control means for said motor comprising a manually operable switch and a limit switch in series, means for adjusting the limit switch to determine the tension position at which said limit switch will open to stop said motor irrespective of the manually operable switch, switch means normally closed in shunt across the limit switch whereby to render the limit switch normally ineffective during automatic tensioning control of said motor, normally closed switch means in series with the automatically operable switch means first mentioned, and means for opening both of the last mentioned switch means for rendering tension adjustment subject to manual control and rendering said manual control subject to the predetermined adjustment of the limit switch.

5. In a device of the character described, the combination with a reel mounted for indexing movement and comprising a plurality of roll arbor supports, manually adjustable brake means for individually retarding rotation of the respective roll arbors, a tensioning belt adjustable to and from a roll supported on one of said arbors

and provided with guides, a belt arm for at least one of said guides adjustable to vary the tensioning pressure of the belt on the roll with which it is engageable, a rock shaft upon which said arm is mounted for tension adjustment, a motor provided with driving connections to said rock shaft for the oscillation thereof in tension increasing and tension decreasing directions, guide means for a web withdrawn from the tension roll and including a tension responsive roll, an arm upon which the last mentioned roll is mounted for tension responsive movement, switch means connected to the last mentioned arm to be actuated thereby and including a tension increasing switch and a tension decreasing switch oppositely movable and connected in circuit with said motor, indicating means including a stationary part and a part connected with said arm for showing the proper tension position of the tension responsive arm, a paster arm movable between advanced and retracted positions, switch means operable in advance of said arm and in circuit with said tension increasing and decreasing switches for cutting off the current thereto upon the advance of said paster arm, and means for manually adjusting the position of the belt arm to control the tension position of the belt when the paster arm is advanced.

6. The device of claim 5 in which means for manual adjustment of the belt arm comprises a manually operable switch and circuit connections therethrough to said motor, and a limit switch in

series with the manually operable switch for pre-determining a proper tension position of the belt arm and interrupting motor operation at said position, said limit switch comprising an actuated part and said arm having in connection therewith an actuating part for transmitting movement to said actuated part for the opening of the limit switch.

7. The device of claim 5 in which means for manual adjustment of the belt arm comprises a manually operable switch and circuit connections therethrough to said motor, and a limit switch in series with the manually operable switch for pre-determining a proper tension position of the belt arm and interrupting motor operation at said position, said limit switch comprising an actuated part and said arm having in connection therewith an actuating part for transmitting movement to said actuated part for the opening of the limit switch, together with an auxiliary switch normally closed in shunt across the limit switch to preclude the opening of the motor circuit by the limit switch during automatic tension control, the said auxiliary switch being provided with connections for the opening of said switch in the course of movement of the paster arm, whereby the initial seating of the paster arm preliminary to a pasting operation will leave the belt arm subject to the control of the limit switch.
